UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

THROAT-PLATE FOR SEWING-MACHINES.

1,263,088.

Specification of Letters Patent.

Patented Apr. 16, 1918.

Application filed July 20, 1915. Serial No. 40,887.

To all whom it may concern:

Be it known that I, CHESTER McNEIL, a citizen of the United States, residing at Chicago, in the county of Cook, State of Illinois, have invented certain new and useful Improvements in Throat-Plates for Sewing Machines, of which the following is a description, reference being had to the accompanying drawing and to the figures of reference marked thereon.

The invention relates to new and useful improvements in throat plates for sewing machines and more particularly to a throat plate which is adapted to be used in connection with a stitching mechanism for forming a flat seam.

An object of the invention is to provide a throat plate adapted to coöperate with two pairs of needles arranged one in rear of the other, wherein the front pair of needles is spaced a greater distance apart than the rear needles, with a stitch tongue for the front pair of needles which stitch tongue terminates in advance of the rear needles, the throat plate having a space in rear of said stitch tongue for the rear pair of needles.

In the drawings:—

Figure 1 is a plan view of a throat plate having my improvements;

Fig. 2 is a view showing the end of a cylindrical work support with my throat plate thereon and also the feed dog which coöperates with said throat plate;

Fig. 3 is a view similar to Fig. 2 showing the presser foot in place over the feed dog;

Fig. 4 is a view partly in vertical section and partly in plan showing the throat plate, the feed dog, the presser foot, the needles and the loopers which coöperate with the same;

Fig. 5 is a perspective view of a throat plate having a slightly modified form of the invention;

Fig. 6 is a perspective view of the feed dog and stitch tongue which coöperates with the throat plate shown in Fig. 5; and

Fig. 7 is a bottom plan view showing more or less diagrammatically the seam formed on my throat plate.

I have shown my improved throat plate 1 as secured to the free end of a cylindrical work support 2 by suitable screws 3—3. Said throat plate is provided with spaced parallel openings 4—4 which receive the

outer webs of the feed dog 5. Said throat plate is provided with other openings 6—6 and 7 for other webs on the feed dog. The throat plate is provided with an opening 8 which is adapted to receive the needles 9—9 and 10—10. A looper 11 coöperates with the front pair of needles 9—9 beneath the throat plate while a looper 12 coöperates with the rear pair of needles 10—10 beneath the throat plate. There is suitable cross thread laying device 9^a which coöperates with the needles 9—9 above the work support and likewise cross thread laying device 10^a which coöperates with the needles 10—10 above the work support. It will, therefore be apparent that my improved throat plate 70 is adapted to be used in connection with two independent stitching mechanisms, one in rear of the other. It will be noted that the needles 9—9 are spaced a greater distance than the needles 10—10 so that the 75 stitches formed by the needles 10—10 will be laid upon the cross threads joining the needle loops of the stitches made by the needles 9—9.

The throat plate 1 has a stitch tongue 13 80 which projects rearwardly into the opening 8. The needles 9—9 pass along the opposite sides of this stitch tongue 13, as clearly shown in Fig. 2. This stitch tongue 13 is substantially equal to the width of the space 85 between the needles and said stitch tongue terminates directly in rear of the needles 9—9. The looper thread of the looper 11 is laid across this stitch tongue 13 and as the looper thread slides off the stitch tongue 90 it will be stitched down by the threads of the needles 9—9.

Above the work support is a presser foot 13^a which is provided with a needle opening 14. Said presser foot is also provided with 95 an opening 16 for the needles 10—10. A stitch tongue 17 extends into said opening and the cross thread of the device 10^a is laid across the same.

My improved throat plate is especially 100 adapted for making a flat seam wherein the edges of the sections of fabric are abutted. The needles 9—9 enter the fabric sections at a distance back from the abutted edges which pass centrally over the stitch tongue 13. The 105 looper thread joining the needle's loops of the needles 9—9, as above noted is laid across this stitch tongue 13 and the stitch

tongue prevents buckling of the fabric edges during the setting of the stitches of the widely spaced needles. The free space in rear of the stitch tongue permits the closely spaced needles to form stitches which tie down these cross threads of the first stitches and which also tie down the loose ends of the threads of the fabric.

In Figs. 5 and 6 I have shown a slightly modified form of the invention. The throat plate 1 has spaced openings 4—4 and the opening 7 for the feed dog. It also has an enlarged opening 18 located centrally between the openings 4—4. The feed dog 5 has its webs at the forward end between the side webs cut away and a plate 19 is secured to the feed dog by a suitable screw 20. This plate 19 is slotted at 21 and 22 to receive respectively the needles 9—9 and the plate 20 extends between the needles as at 23 forming a stitch tongue; this stitch tongue terminates in advance of the closely spaced needles 10—10 in the hammer above described, in connection with the stitch tongue 13. In 25 other words, I have shown in Figs. 5 and 6 that I consider the placing of the stitch tongue on the feed dog a full equivalent of the placing of the stitch tongue on the throat plate.

In Fig. 7 I have shown more or less diagrammatically, a bottom plan view of a seam stitched on my improved throat plate. The fabric is indicated at F, the thread of the needle 9—9 is indicated at $n-n$ and the 35 thread of the looper 11 coöperating with these needles is indicated at 1. The threads of the needles 10—10 are indicated at $n'-n'$ and the thread of the looper 12 which coöperates with these needles is indicated 40 at 1'.

It is obvious that minor changes in the details of construction and the arrangement of parts may be made without depart-

ing from the spirit of the invention as set forth in the appended claims.

Having thus described my invention what I claim as new and desire to secure by Letters Patent, is:—

1. The combination of a throat plate and pairs of needles arranged one in rear of the other, the needles of the front pair being spaced a greater distance than the needles of the rear pair, a looper coöperating with each pair of needles below the throat plate, a cross thread laying device coöperating with each pair of needles above the throat plate, said throat plate being provided with an opening for the pairs of needles and with a stitch tongue which extends into the needle opening therein between the front pair of 60 needles and terminates adjacent the rear pair of needles.

2. The combination of a throat plate, a presser foot, and pairs of needles arranged one in rear of the other, said needles of the front pair being spaced a greater distance than the needles of the rear pair, a looper coöperating with each pair of needles below the throat plate, a cross thread device coöperating with each pair of needles above the 70 throat plate, said throat plate and presser foot being provided with an opening for the pairs of needles, the throat plate having a stitch tongue extending into the needle opening therein and coöperating with one pair of 75 needles and the presser foot having a stitch tongue extending into the needle opening for the other pair of needles and coöperating with said needles.

In testimony whereof, I affix my signature, in the presence of two witnesses.

CHESTER McNEIL.
